(57) CLAIM

The ornamental design for a handbag as shown and described.

DESCRIPTION

1. Handbag

1.1 : Perspective

1.2 : Front

1.3 : Back

1.4 : Right

1.5 : Left

1.6 : Bottom

1.7 : Top

Evenly dashed broken lines in the drawings constitute stitching of the handbag in the claimed design.

Dot-dash broken lines represent features that form no part of the claimed design.
